US00D615983S

(12) **United States Design Patent**
Aoki

(10) **Patent No.:** **US D615,983 S**
(45) **Date of Patent:** **** May 18, 2010**

(54) **ADAPTER FOR MEMORY CARD**

(75) Inventor: **Yoshitaka Aoki**, Tokyo (JP)

(73) Assignee: **Sony Corporation**, Tokyo (JP)

(**) Term: **14 Years**

(21) Appl. No.: **29/343,544**

(22) Filed: **Sep. 15, 2009**

Related U.S. Application Data

(62) Division of application No. 29/300,961, filed on Jun. 5, 2008, now abandoned.

(57) **CLAIM**

The ornamental design for an adapter for memory card, as shown and described.

DESCRIPTION

FIG. 1 is a perspective view of a first embodiment of an adapter for memory card showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The portions indicated in broken lines are for illustrative purposes only and form no part of the claimed design.
